US00D753685S

(12) **United States Design Patent**
Zimmerman et al.

(10) **Patent No.:** **US D753,685 S**
(45) **Date of Patent:** **** Apr. 12, 2016**

(54) **THERMAL CYCLER DISPLAY SCREEN
WITH GRAPHICAL USER INTERFACE**

(71) **Applicant:** **LIFE TECHNOLOGIES
CORPORATION**, Carlsbad, CA (US)

(72) **Inventors:** **Sean Zimmerman**, San Diego, CA (US); **Scott Rickes**, San Diego, CA (US); **Joseph Lee**, San Diego, CA (US); **Michael Joseph Jackson**, San Diego, CA (US)

(73) **Assignee:** **Life Technologies Corporation**, Carlsbad, CA (US)

(**) **Term:** **14 Years**

(21) **Appl. No.:** **29/445,006**

(22) **Filed:** **Feb. 6, 2013**

(51) **LOC (10) Cl.** **14-04**

(52) **U.S. Cl.**

USPC **D14/486**
